HYDRO CYCLONE

Maurice D. Woodruff, Springfield, Ohio, assignor to The Bauer Brothers Co., Springfield, Ohio, a corporation of Ohio

Filed Apr. 1, 1959, Ser. No. 803,435
5 Claims. (Cl. 209—211)

This invention relates to centrifugal separators, and particularly to hydrocyclones for separating a liquid suspension of solids into accepted and rejected fractions. Although not so limited, the invention has especial reference to a conical separator, sometimes known as a cleaner, used in paper making processes to separate clean, usable fibrous material from a flowing liquid pulp suspension which, in addition to the usable material contains unwanted dirt and coarse particles. A device of this kind is disclosed, for example, in the patent to E. W. Samson et al., No. 2,377,524, issued June 5, 1945, and includes a means defining a separating chamber receiving through an inlet at the base end, the liquid suspension of solids. By virtue of the arrangement of the inlet the suspension is discharged tangentially into the separating chamber in a manner to progress from one end to the other in a swirling motion. The apex end of the separating chamber is open, as is the base end wherein a nozzle or finder is located to receive and guide an inner vortex in which is comprised the accepted fraction of solids, the rejected fraction discharging through the apex end of the chamber. The nozzle arrangement at the base end of the separating chamber is considered as providing for "overflow," with "underflow" taking place at the apex end. These terms, however, do not denote attitude limitations since the separator device can be mounted in any position which is convenient from an installation standpoint, the speed of movement of the liquid suspension through the separator making the device operationally independent of gravity.

In widespread use, hydrocyclonic cleaners as described nevertheless have certain limitations, for example, a tendency to work at something less than maximum efficiency and a tendency to draw air or liquid into the separating chamber through the underflow end where it is mixed with the accepted fraction and travels with it to the paper making machinery.

A cause of loss of efficiency in the cleaner has been known to lie in the overflow nozzle. Eddy currents form in the region of the inlet and move along the overflow nozzle to the entrance end thereof where portions of the currents are drawn into the nozzle and carried out with the accepted fraction and before the cleaner has had opportunity to separate out rejectable material.

The entrainment of air with the accepted fraction may be undesirable as affecting the qualities of the pulp supplied to the paper making machinery from the separator. Such entrainment can be avoided by submerging the underflow end of the separator in a liquid bath but it has been necessary to avoid this recourse since the cleaner will then draw liquid into its separating chamber and discharge it with the accepted fraction, the result being as in the case of air entrainment a reduction in quality of the issuing pulp. Accordingly, the cleaner devices heretofore have been operated either with their underflow ends communicating freely with the atmosphere, or where the exclusion of air is particularly important, means are provided to create a vacuum at the underflow end so that the apex or underflow end of the cleaner is in communication with a source of negative pressure precluding reverse flow into the separating chamber.

The object of the invention is to simplify the construction as well as the means and mode of operation of

2

cyclone cleaners, whereby such cleaners may not only be economically manufactured, but will be more efficient and satisfactory in use, adaptable to a wide variety of applications, and be unlikely to get out of order.

5 A further object of the invention is to significantly improve the efficiency of the cleaner and to prevent induction at the underflow end of the cleaner.

10 It is another object of the invention to modify the construction of the overflow nozzle to the end that eddy currents may be forced away from the entrance end of the nozzle thus minimizing a bypassing flow of dirt rich pulp.

15 It is a further object of the invention to obviate the need for vacuum devices and the like in preventing reverse flow at the apex end of the cleaner, the improvement in the cleaner contemplated by the invention inhibiting flow into the separating chamber through the underflow end and enabling such end to be submerged in liquid with a corresponding increase in overall effectiveness.

20 A further object of the invention is to provide a hydrocyclone cleaner possessing the advantageous structural features, the inherent meritorious characteristics and the mode of operation herein mentioned.

25 With the above and other incidental objects in view as will more fully appear in the specification, the invention intended to be protected by Letters Patent consists of the features of construction, the parts and combinations thereof, and the mode of operation as hereinafter 30 described or illustrated in the accompanying drawings, or their equivalents.

Referring to the accompanying drawing wherein is shown one but obviously not necessarily the only form of embodiment of the invention,

35 FIG. 1 is a view in longitudinal section, and partly diagrammatic, of a hydrocyclonic cleaner from the prior art, showing the manner in which eddy currents are formed and may join with the accepted fraction exiting through the overflow nozzle;

40 FIG. 2 is a view like FIG. 1, showing a fragmentary portion of the apex end of the separator and an underflow nozzle and shield fastened thereto;

45 FIG. 3 is a view similar to FIG. 1 showing a hydrocyclonic cleaner or separator modified in accordance with a concept of the present invention;

FIG. 4 is a view showing an underflow nozzle submerged in a liquid bath; and

FIG. 5 is a view in cross-section taken substantially along the line 5—5 of FIG. 3.

50 Like parts are indicated by similar characters of reference throughout the several views.

Referring to FIGS. 1 and 2, a hydrocyclonic device of the kind to which this invention has especial reference comprises a shell 10 having a unitary structure, as by 55 being made of a plurality of sections bolted or otherwise secured together. Included in the shell 10 is a portion 11 having the shape of a truncated cone, the interior of portion 11 being hollow to define a separating chamber 12 and the opposite ends of such chamber opening through 60 the base and apex ends of the cone. Further comprised in the shell 10 is a cylindrical portion 13 on the base end of conical portion 11 and in superposed aligned relation thereto. A back wall 14 of portion 13 closes what may be considered to be the head of the device, except for the 65 installation therein of a tubular nozzle 15. The latter is concentrically arranged in the shell 10 and projects through and beyond the wall 14 at its opposite ends. The nozzle 15 thus has an outer end projecting outside the shell 10 and an inner end within the shell, the enclosed 70 portion of the nozzle extending a substantial distance within the shell, as, for example, approximately to the

inner end of cylindrical portion 13 as shown. The nozzle 15 is open at its ends for a free flow therethrough while within the shell it occupies a position in spaced parallel relation to the walls of portion 13.

At a point intermediate the inner end of the nozzle 15 and back wall 14 there further is formed in cylindrical portion 13 an inlet 16 communicating through a laterally projecting boss 17 with the exterior of the shell, the boss 17 being adapted to be connected in a system to supply thereto a pulp suspension under pressure. The arrangement is one to introduce the pulp suspension into the shell 10 tangentially of the walls thereof, the continued application of pressure at the inlet causing the pulp suspension to progress from the base end of the device to the apex end in a swirling motion inducing centrifugal forces. As a result of these forces there is left in the axis of the device an area of low pressure creating what may be considered to be an inner vortex moving contra to the outer vortex, that is in a direction from the apex end to the base end. The nozzle 15 serves in this connection as a vortex finder, its inner end extending inwardly of the shell to receive the inner vortex and to conduct it out of the shell, the outer end of the nozzle being adapted for connection in a suitable conduit to conduct the materials caught in the inner vortex to a subsequent process step. In accordance with the concept and mode of operation of the cleaner, relatively light and clean fibers from the liquid pulp suspension are gathered up by the inner vortex and conducted out the base end of the device as the accepted fraction while the remainder of the liquid suspension leaves the device through the apex end thereof.

As shown in FIG. 2, there conventionally is installed on such apex end a conical nozzle 18 constituting an extension of the conical portion 11 and termed the underflow nozzle, in contrast to the nozzle 15 termed the overflow nozzle. The nozzle 18 is attached to the apex end of the portion 11 in a suitable manner, as through a lock plate 19 and bolts 21 and may be enclosed as shown by a shield 22.

The construction and arrangement of parts is one to produce a complex pattern of forces especially characterized by decreasing pressure from the peripheral wall to the axis of the device accompanied by a reverse velocity effect, the angular velocity increasing from periphery toward the axis. The pressure differential causes movement in the liquid suspension from the outer wall of the shell toward the center line thereof. Fiber and dirt, in passing through fields of successively increasing centrifugal force, tend to slow down in relation to their inward radial travel. A dirt particle reaching a centrifugal field which counterbalances the radial flow will be carried in this field until it reaches the exit.

The high rotative speed of the pulp suspension produces shear effects at the margins of its adjacent layers and creates a liquid free core extending the full length of the cleaner center line and containing a partial vacuum. In effect it is a passageway for movement of air. Shear forces wipe entrained air bubbles off the fiber and they are forced immediately into the core. The light, clean fibrous material moves with the liquid to the inner vortex. This, as noted, becomes the accepted fraction which moves in a reverse sense toward the base end of the device and exits through the nozzle 15.

The pressure difference noted to exist between the outer wall of the cleaner and the axis thereof exists also within the head or cylindrical portion 13 wherein the pressure at the outer wall of the head is greater than in the region of the overflow nozzle 15. This results in an eddy current, here depicted by the arrows 20, which moves from the outer wall laterally in parallel relation to the back wall 14 to the wall of the overflow nozzle where it is constrained to turn and move along the length of the nozzle toward the inner or entrance end thereof. Since the eddy current originates in the region of the outer wall it carries with at a dirt rich portion of the pulp, and, as this

attempts to pass the opening into the overflow nozzle, some of the dirt rich suspension is drawn into the inner vortex and contaminates the relatively dirt free fraction entering the overflow nozzle.

5 A part of the instant inventive concept is that of a means to obviate the harm done by eddy currents by directing the currents away from the entrance end of the overflow nozzle. In accordance with such inventive concept it is proposed to modify the exterior of the nozzle in such manner as to provide an enlargement at its inner end which will deflect those eddy currents traveling along the nozzle outward causing them to rejoin the main body of rotating suspension and avoiding opportunity for portions of the suspension to bypass the function of the cleaner by escaping directly into the overflow nozzle.

10 15 A preferred form of such a modified nozzle is shown in FIG. 3. There, a head 23 of a cleaner is provided with an inlet 24 and an overflow nozzle 25, the construction and arrangement of parts being the same as that shown in FIG. 1 except that the nozzle has a wall of gradually increasing thickness in a manner to form a sloping exterior surface 26. At the inner end of the nozzle the surface 26 terminates in an abruptly flaring curvature 27. The result, as indicated by the arrows 28 which depict the 20 movement of an eddy current, is that as the current moves along the exterior of nozzle 25 it is gradually constrained by the sloping surface 26 to an outward course, and, at the final curvature 27, positively is deflected and directed outward toward the wall of the shell and away 25 from the entrance to the nozzle. That the eddy currents are in fact so diverted is substantiated by tests showing a significant reduction of dirt in the clean accepted fraction.

30 35 The diverting of the eddy currents in the manner described not only deflects dirt rich suspension from the entrance end of the overflow nozzle but also introduces a new factor in the pattern of forces at work in the separating chamber 12. The precise nature of this effect, and the reasons therefor, are believed to be not fully understood. The result thereof, however, is, in accordance with a further concept of the invention, to significantly limit or to eliminate insuction through the underflow nozzle at the apex end of the cleaner. As heretofore noted, insuction of either air or water frequently is undesirable 40 45 so that vacuum systems applied to the underflow nozzles are in common use. These systems, in addition to being relatively costly and bulky of installation, have been impractical to apply on small diameter cleaners. The instant invention, therefore, makes a significant advance in the cleaner art in obviating the need for vacuum systems. Moreover, it is a specific part of the invention to use a modified cleaner as disclosed in combination with a liquid bath, running the cleaner with the underflow nozzle 30 submerged within a body of water 31 which arrangement 50 55 has been shown to achieve a maximum efficiency of the cleaner.

60 65 From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

70 75 While in order to comply with the statute the invention has been described in language more or less specific as to structural features, it is to be understood that the invention is not limited to the specific features shown, but that the means and construction herein disclosed comprise but one of several modes of putting the invention into effect, and the invention is therefore claimed in any of its forms or modifications within the legitimate and valid scope of the appended claims.

Having thus described my invention, I claim:

75 1. A hydrocyclonic device for separating a liquid sus-

pension of solids into accepted and rejected fractions, including a shell providing a separating chamber having an opening at one end for discharge of rejected fractions, a nozzle having a through opening projecting into said chamber at its opposite end to define an outlet for discharge of accepted fractions, means defining a tangential inlet to said chamber at said opposite end for introducing a liquid suspension, causing it to follow a swirling path to said one end of the chamber and induce a central axial reverse flow vortex from said one end of the chamber to the inner end of said nozzle entraining accepted fractions, the opening through said nozzle and the opening at said one end of said chamber being axially aligned, and externally projected sloping means on said nozzle in surrounding relation to the inlet thereto at its end within said chamber to deflect eddy currents, resulting from the delivery of the liquid suspension through said tangential inlet, outwardly and in paths angularly inclined to the chamber wall and away from said nozzle inlet.

2. A hydrocyclonic device for separating a liquid suspension of solids into accepted and rejected fractions, including a shell providing a separating chamber open at its opposite ends for discharge of the respective fractions, means defining a tangential inlet to said chamber at its end having the opening for discharging the accepted fraction, an overflow nozzle having its inlet projected within said chamber to define the opening from said chamber for the accepted fraction, means mounted to define the opening from said chamber for discharging the rejected fraction therefrom, means providing a liquid bath submerging the discharge end of the last named means and means on said nozzle for angularly deflecting eddy currents, consequent to the introduction of a liquid suspension of solids to said chamber through said tangential inlet, to the chamber wall, and operative to inhibit inflow of liquid from the liquid bath to said nozzle.

3. A hydrocyclonic device for separating a liquid suspension of solids into accepted and rejected fractions, including a shell providing a separating chamber having an inlet for tangential admission of a liquid suspension, a nozzle having a through opening mounted to project in said chamber and define an opening therefrom adjacent

said tangential inlet for discharge of accepted fractions, said nozzle being in spaced relation to the chamber wall, means defining an opening from said chamber at its opposite end for discharge of rejected fractions, said chamber, nozzle and means defining the tangential inlet to said chamber being so arranged that on tangential admission of a liquid suspension a swirling flow thereof is produced adjacent the chamber wall to carry rejected fractions through the opening at said opposite end of said chamber and accepted fractions to and through said nozzle and means on said nozzle adjacent the inlet thereto in said chamber providing an external lateral projection to inhibit flow of dirt rich fractions through said nozzle under the influence of eddy currents consequent to delivery of the suspension through said tangential inlet.

15 4. A hydrocyclonic device according to claim 3, characterized by said opening from the opposite end of said chamber being defined by a projected nozzle and means providing a liquid bath submerging said projected nozzle, the means forming the projection about the inlet to said nozzle being operative to inhibit flow from the liquid bath into said chamber.

20 5. A hydrocyclonic device according to claim 3, characterized in that said nozzle has a generally uniform internal cross sectional dimension and an external configuration providing a gradual expansion thereof in a lateral sense toward the inlet end thereof whereby on tangential admission of the liquid suspension the eddy currents consequent thereto will be angularly deflected to the wall of said chamber and from the inlet to said nozzle within the chamber.
